OSCAR NYGAARD, OF SAUGUS, MASSACHUSETTS, ASSIGNOR TO BERNITZ FURNACE APPLIANCE COMPANY, OF BOSTON, MASSACHUSETTS, A CORPORATION OF MASSACHUSETTS

TUYÈRE AND SUPPORTING MEANS THEREFOR

Application filed January 11, 1930. Serial No. 420,142.

This invention relates to tuyères and to furnaces in which tuyères are used.

In furnaces of this type tuyères made of cast iron have, so far as I have been able to learn, been used universally heretofore. It is a matter of common experience to those skilled in this art that such tuyères give much trouble due to their tendency to melt down and burn out. Furthermore, this tendency must be constantly borne in mind in operating furnaces of this type and this fact imposes certain limitations or restrictions on the results which can be obtained from these furnaces. This condition has been further aggravated by the use of preheated air which has become a common practice in recent years. Even when operated with due care the tuyères disintegrate or wear out after a short time and it is usually necessary to renew them at relatively frequent intervals.

The present invention deals with these conditions and it aims to improve the construction both of tuyères and of furnaces in which tuyères are used, with a view to minimizing these objections.

The nature of the invention will be readily understood from the following description when read in connection with the accompanying drawings, and the novel features will be particularly pointed out in the appended claims.

In the drawings,

Figure 1 is a vertical sectional view, partly in elevation, of a furnace embodying features of this invention;

Figs. 2 and 3 are plan and side views, respectively, showing individual tuyères and the means for supporting them in the furnace;

Fig. 4 is a perspective view of the bracket construction for supporting the tuyères;

Figs. 5 and 6 are perspective views of a tuyère embodying features of this invention;

Figs. 7 and 8 are plan and side views of another form of tuyère constructed in accordance with this invention; and

Figs. 9 and 10 are plan and side views, respectively, of a top plate which is used at the upper ends of the rows of tuyères shown in Fig. 1.

Fig. 1 shows the invention embodied in a furnace which for purposes of disclosure has been shown equipped with the well known Taylor stoker. This furnace has the usual inclined retorts or fuel channels alternating with rows of tuyères, one row of tuyères being shown at 2, the tuyères and retorts cooperating to support the fuel bed. The coal hopper of the stoker mechanism is shown at 3, the ram at 4, and the front, side and rear furnace walls at 5, 6 and 7, respectively. Air under pressure is forced into the chamber 8 immediately below the fuel bed support, as is usual in furnaces of this type, and is discharged through the tuyères into the fuel bed. In fact, the entire organization may be of the same general nature as that of the ordinary stoker furnace except for certain features which will be described more particularly hereinafter.

An important feature of this invention resides in the construction and mounting of the tuyères. While it has been proposed heretofore to make tuyères of non-metallic materials which are more highly refractory than cast iron, none of these prior constructions has gone into practical use, so far as I have been able to learn. A serious difficulty encountered in the manufacture of a non-metallic refractory tuyère is to devise a construction which will have the necessary degree of mechanical strength to withstand the rough usage to which devices of this kind must necessarily be subjected. The use of materials of this kind also is made all the more difficult by the fact that its degree of expansion and contraction is very different from that of the iron supports on which it must be mounted, and unless provision is made for accommodating such expansion and contraction the tuyères will be broken. This invention deals especially with these problems.

Referring more particularly to Figs. 2 to 6, inclusive, which illustrate one form of tuyère embodying this invention, it will be observed that the tuyère there shown comprises a plate-like bottom portion 10, the lower surface of which preferably is substantially flat. A series of lugs 12 project from the upper side

of this member 10, these lugs being separated from each other by grooves 13. The grooves lead out of and radiate from a chamber 14 formed in the upper side of the tuyère. Both the top and bottom surfaces of the tuyère are substantially flat so that one tuyère will set on another in overlapping relationship as shown in Figs. 2 and 3, the rearward end of the upper tuyère coming approximately to the rearward end of the flat upper surface of the lower tuyère. Lying rearwardly of this flat surface is what may be regarded as the nose portion 15 of the tuyère, to distinguish it from the body part which lies forwardly of the tapered nose. It will be clear from an inspection of Figs. 2, 3 and 5 that this nose portion, as shown, has a rounded outline and that it is tapered longitudinally and rounded laterally. This formation is of advantage in enabling the tuyère to shed the coal and ash, or in other words, to prevent these materials from loading up the upper surfaces of the tuyères and tending to obstruct the flow of air.

As shown in Fig. 2 each tuyère spans the air channel 16 lying between the adjacent air channel walls or retort walls 17-17. When the tuyères are located in their normal overlapping relationship, as shown in Figs. 2 and 3, the air chamber 14 will be in free communication with the chamber 8, Fig. 1, in which a slight positive air pressure is constantly maintained when the furnace is in operation. Since the grooves 13 radiate from this chamber 14, they conduct an ample supply of air into the fuel bed. Some of these grooves extend forward and open on to the tapered surface of the nose 15 while others are directed laterally and open at the sides of the tuyère. By making the tuyère very much thicker than the ordinary cast iron tuyère, it can be made from silicon carbide, carborundum, or other refractory non-metallic material and still have ample mechanical strength, while at the same time affording plenty of cross-sectional area for the grooves so that an abundant supply of air can be discharged into the fuel bed. Preferably the inner ends of the lugs 12 are each tapered to an edge, as clearly shown in the drawings, so as to reduce their resistance to the flow of air, and the grooves 13 between adjacent lugs grow narrower for a short distance as they extend away from the chamber 14 and then gradually become wider to provide additional cross-sectional area for the air as it expands.

For the purpose of supporting the tuyères in their operative positions, brackets 20, Figs. 2, 3 and 4, are secured to the channel walls 17, each bracket having a groove in the outer side thereof to fit over the upper edge of its respective channel wall. The channels are provided with lugs 21 cast on them and each bracket has a corresponding lug 22 to rest on the respective lugs 21, the two lugs being se-

cured together by a bolt 23. Preferably each lug 22 is slotted to receive the bolt so that the bracket may be adjusted relatively to the channel wall. The brackets are arranged in pairs, the two members of each pair being located in alignment with each other on opposite sides of an air channel 16. In the particular construction shown each bracket has four steps and each pair of brackets is designed to support two tuyères.

In order to hold the tuyères against any substantial movement in a horizontal plane, each bracket is provided with two inwardly extending lugs 24-24', Fig. 4, and each tuyère is notched or recessed at the opposite edges of its heel portion, as shown at 25, Fig. 6, to receive one pair of lugs. It will be clear from an inspection of Figs. 4 and 6 that the heel portion of the tuyère shown in the latter figure can be placed on the two steps *b*-*b* of the brackets 20-20, Fig. 4, by lowering this tuyère vertically onto these steps and guiding the lugs 24-24' into the two notches 25-25 in the heel portion of the tuyère. The extreme forward or left-hand end of the plate portion 10 of the tuyère will fit between the steps *c*-*c*, and the shoulders 26-26 will rest on these steps, the upper surface of the tuyère being substantially flush with the top steps *d*-*d*. A lower tuyère is similarly supported partly on the steps *a*-*a* and partly on the body portion of the tuyère immediately below it, and is held against substantial movement out of this position in a horizontal plane by the lugs 24'-24' entered in the sockets 25-25 of its respective tuyère. The lugs fit loosely in the recesses and a suitable clearance is provided between the heel end of the tuyère and the brackets so that each tuyère is free to expand and contract relatively to its supporting means, while at the same time being held against any substantial movement away from its operative position. The tuyères can simply be dropped into their operative positions or lifted out of them.

In some cases it may be desirable to use a centering pin such as that shown at 27, Fig. 3, to enter sockets 28 and 29, Figs. 5 and 6, in overlapping tuyères. If such a pin is used it preferably is made of silicon carbide or other refractory non-metallic material. In most constructions, however, such a pin is not required.

A somewhat different embodiment of the invention is shown in Figs. 7 and 8. The tuyères shown in these figures are substantially like those shown in Figs. 2, 3, 5 and 6 except that the former constructions are each provided with a second series of lugs 30 located at the lower side of the plate-like member 10. These lugs are separated by air conducting grooves 31. It will be clear from an inspection of Figs. 7 and 8 that the lower lugs 30 are so spaced and arranged that when one tuyère is overlapped upon another in normal

relationship the lower lugs of the upper tuyère will register with the upper lugs of the lower tuyère. Consequently, the grooves 31 between the lower lugs will register with the grooves 13 between the upper lugs. This construction is preferred where it is desired to make the tuyère of substantially greater thickness than those shown in Figs. 5 and 6. In this arrangement, also, the grooves 31 radiate from a central air chamber in the lower side of the tuyère in the same general manner that the grooves 13 radiate from the chamber 14.

At the upper end of each line of tuyères, such as that shown in Fig. 1, a cap plate may be used constructed as shown at 32, Figs. 1, 9 and 10. This cap has a socket 33 to receive a pin like the pin 27, Fig. 3, to hold the cap in alinement with the tuyère immediately below it, and its heel end is reduced in thickness to fit between the walls of the air channel. Preferably, also, it is provided with a socket or slot 34 to receive a key 35, Fig. 1, projecting from the lower side of a metal plate 36 which may be held between the retort walls and assists in holding the cap 32 in its operative position.

The tuyère provided by this invention has been found to satisfy the practical requirements for a device of this character. It is sufficiently sturdy and substantial in construction to withstand the rough usage to which these devices are subjected, and because it is more highly refractory than iron it avoids the objectionable features of tuyères of the common constructions. In addition, the tuyère provided by this invention permits the location of the nose farther forward in the fuel bed where it can deliver a part of the air deeper into the bed than has been possible with iron tuyères due to the liability of the latter tuyères to burn out or melt down under these conditions. These tuyères can readily be molded from silicon carbide or other refractory materials, and because of their peculiar design do not require the use of cores.

It is preferable to make the plate-like bottom 10 at least an inch in thickness. In a typical construction this plate is made one and one-half inches thick and the overall thickness of the tuyère is made approximately three inches, these tuyères thus being very much larger than the ordinary iron tuyère. While this overall thickness could be reduced somewhat, I prefer to use a thickness of at least two inches and I consider it a much better practice to increase this thickness quite substantially. On the other hand, the thickness of the plate-like bottom 10 should not run over three inches and the overall thickness should not be more than six inches.

While I have herein shown and described preferred embodiments of my invention, it will be understood that the invention may

be embodied in other forms without departing from the spirit or scope thereof.

Having thus described my invention, what I desire to claim as new is:

1. In a stoker furnace, the combination of an inclined fuel bed support including an inclined channel for conducting air to the fuel bed, and a series of refractory non-metallic tuyères overlapping each other and covering the top of said air channel for a substantial portion of its length, each tuyère spanning said channel and having a body portion recessed on its upper side and cooperating with the tuyère next above it to form an air chamber, each tuyère being provided also with a nose portion projecting from said body part and extending rearwardly beyond the rear end of the tuyère next above it, each tuyère also having grooves leading from said chamber through the upper side of said body part and opening on to the upper surface of said nose. 80 85

2. In a stoker furnace, the combination of an inclined fuel bed support including an inclined channel for conducting air to the fuel bed, a series of refractory non-metallic tuyères overlapping each other and covering the top of said air channel for a substantial portion of its length, brackets carried by the walls of said air channel and supporting said tuyères, said tuyères and brackets having cooperating parts for loosely holding the tuyères in their operative positions but permitting them to expand and contract. 90 95

3. In a stoker furnace, the combination of an inclined fuel bed support including an inclined channel for conducting air to the fuel bed, a series of refractory non-metallic tuyères overlapping each other and covering the top of said air channel for a substantial portion of its length, brackets carried by the walls of said air channel and provided with steps on which said tuyères are supported in their operative positions, said brackets having lugs and said tuyères being recessed to loosely receive said lugs, whereby the tuyères are held by said lugs and brackets in their operative positions and are permitted to expand and contract under 100 105 110 changes in temperature. 115

4. In a stoker furnace, the combination of an inclined fuel bed support including an inclined channel for conducting air to the fuel bed, a series of refractory non-metallic tuyères overlapping each other and covering the top of said air channel for a substantial portion of its length, brackets carried by the walls of said air channel and provided with steps on which said tuyères are supported in their operative positions, each of said tuyères including a nose portion to project into the fuel bed and a heel portion resting on said brackets, grooves in the upper surfaces of said tuyères extending forward into said 120 125 130

nose portions and serving to discharge air into the fuel bed, said heel portions having recesses in opposite edges thereof and said brackets having lugs to enter said recesses and hold the tuyères loosely against movement out of their operative positions in a horizontal plane but permitting the tuyères to be moved upwardly out of said positions.

5. A tuyère of refractory non-metallic material comprising a body portion having a relatively large recess in the upper side thereof, a rounded nose extending rearwardly from said body portion and having a rounded and tapered upper surface, and grooves in the upper side of said tuyère leading from said recess to the tapered upper surface of said nose.

6. A tuyère of refractory non-metallic material comprising a body portion having a relatively large recess in the upper side thereof, a rounded nose extending rearwardly from said body portion and having a rounded and tapered upper surface, and grooves in the upper side of said tuyère radiating from said recess with lugs separating adjacent grooves, said body part having a flat upper surface formed partly on said lugs to support the heel portion of another tuyère.

7. A tuyère of refractory non-metallic material comprising a body portion having a relatively large recess in the upper side thereof, a rounded nose extending rearwardly from said body portion and having a rounded and tapered upper surface, grooves in the upper side of said tuyère leading from said recess to the tapered upper surface of said nose, and recesses in the sides of the heel portion of the tuyère for receiving devices for holding the tuyère in its operative position.

8. A tuyère of refractory non-metallic material comprising a flat plate-like member extending substantially from end to end of the tuyère and having lugs integral therewith and projecting from one side thereof with grooves separating said lugs and serving to conduct air to the rearward end of the tuyère, said tuyère having a recess in the upper side thereof into which said grooves open at their forward ends, and a relatively thick nose at the rear end of the tuyère, said nose being formed on and integral with said plate and being tapered longitudinally and rounded laterally.

9. A tuyère of refractory non-metallic material comprising a plate-like member extending substantially from end to end of the tuyère and having two series of lugs extending therefrom, one series at the upper and one at the lower side of the plate with air conducting grooves separating adjacent lugs, the lower series of lugs lying chiefly at the rear of the upper series.

10. A tuyère of refractory non-metallic material comprising a plate-like member extending substantially from end to end of the

tuyère and having two series of lugs extending therefrom, one series at the upper and one at the lower side of the plate with air conducting grooves separating adjacent lugs, and a tapered nose integral with said lugs and plate and having sloping upper surfaces, the lower lugs lying chiefly under said surfaces and the upper lugs lying chiefly in front of said surfaces.

11. A tuyère of refractory non-metallic material comprising a flat plate-like member extending substantially from end to end of the tuyère and having two series of lugs extending therefrom, one series at the upper and one at the lower side of the plate with air conducting grooves separating adjacent lugs, said tuyère having flat upper and lower surfaces to engage additional tuyères located respectively, above and below it, and said lower series of lugs being offset rearwardly with reference to said upper series of lugs.

12. A tuyère of refractory non-metallic material comprising a plate-like member extending substantially from end to end of the tuyère and having two series of lugs extending therefrom, one series at the upper and one at the lower side of the plate with air conducting grooves separating adjacent lugs, and a tapered nose integral with said lugs and plate and having sloping upper surfaces, the lower lugs being spaced and arranged to rest on and register with the upper lugs of another tuyère of the same construction, with the nose of the lower tuyère projecting beyond the end of the nose of the upper tuyère.

13. A tuyère of refractory non-metallic material comprising a plate-like member extending substantially from end to end of the tuyère and having two series of lugs extending therefrom, one series at the upper and one at the lower side of the plate with air conducting grooves separating adjacent lugs, and a tapered nose integral with said lugs and plate and having sloping upper surfaces, recesses in both the upper and lower sides of the tuyère from which the grooves at the opposite sides, respectively, of the tuyère radiate, certain of said upper grooves opening on to the sloping surface of said nose, and the lower grooves lying chiefly under said sloping surface.

OSCAR NYGAARD.
